UNITED STATES PATENT OFFICE.

CHARLES E. HARRIS, OF SAXTON'S RIVER, VERMONT.

TOOL.

SPECIFICATION forming part of Letters Patent No. 481,865, dated August 30, 1892.

Application filed October 7, 1891. Serial No. 403,056. (No model.)

To all whom it may concern:

Be it known that I, CHARLES E. HARRIS, of 5
Saxton's River, in the county of Windham
and State of Vermont, have invented a new
and Improved Tool, of which the following is
a full, clear, and exact description.

My invention relates to improvements in
tools; and the object of my invention is to
produce a tool which is adapted to be used in
10 combination with a hammer or hatchet, which
is especially useful in shingling, clapboarding
or performing similar work, and which
enables the workman to do his work easily
and rapidly, as hereinafter described.

15 To this end my invention consists in a tool
the construction of which will be hereinafter
described and claimed.

Reference is to be had to the accompanying
drawings, forming a part of this specification,
20 in which similar figures of reference indicate
corresponding parts in all the views.

Figure 1 is a side elevation of the tool as
applied to a hammer. Fig. 2 is an enlarged
25 detail side elevation, partly in section, of the
tool; and Fig. 3 is a plain view of the same.

The tool is adapted to be used in connection
with a hatchet or hammer, and as shown in the
drawings it is applied to the latter, the hammer
10 having the usual handle 11, which extends
30 through the head.

The tool proper is held in a socket 12, which
socket is driven into the end of the handle,
and the socket is provided on opposite outer
35 sides with a barbed flange 13, which prevents
its easy removal after it is once driven into
the handle.

The socket is adapted to remain permanently
in the handle and it serves incidentally
40 to hold the hammer-head in place. The socket
is screw-threaded internally and is adapted
to receive the threaded shank 14 of the tool 15,
which tool has a thickened body portion 16,
from one side of which extends a pointed
45 prong 17 and from the other side of which
extends a knife 18.

When the tool is applied to a hammer or
hatchet, the socket 12 is driven into the ham-
mer or hatchet handle, as described, a nut 19
is screwed upon the shank 14 of the tool, and
50 the shank is then screwed into the socket
until the nut 19 bears against the outer end
of the socket.

The tool is preferably arranged at right
angles to the hammer or hatchet, but may be
placed at any convenient angle thereto, and 55
by turning the shank in its socket the tool
may be adjusted so that the knife or prong
will project from either side of the hammer
or hatchet, as desired, thus providing means
for adapting the tool for the use of either a 60
right-handed or left-handed person.

The tool is adapted for a great variety of
uses, some of the more prominent of which
are as follows: By means of the prong 17 a 65
shingle or clapboard may be easily picked up,
which is done by sticking the prong into the
article to be raised, and it will be seen that
the workman by taking hold of the hammer
or hatchet handle will be able to reach much
70 farther than he otherwise could. The prong
also affords an easy means of securing the
tool and hammer or hatchet in place, which is
done by striking the prong into any support.
It is also adapted for use as a scratch-awl and
75 as a support for a chalk-line.

The knife may be used for splitting a shin-
gle or cutting a shingle or clapboard, and
when the tool is not to be used it may be re-
moved from the hammer or hatchet by simply
80 unscrewing it, and the socket which remains
in the handle will serve as a fastening.

Having thus described my invention, I
claim as new and desire to secure by Letters
Patent—

1. An attachment for hammers and hatchets, 85
comprising a body portion having a threaded
shank, a pointed prong, and a knife, all in-
integral with the body, the prong and knife being
on opposite sides of the said body, and an
internally-screw-threaded socket adapted to be 90
secured in the end of the handle, projecting
through the head of the hammer or hatchet,
substantially as described.

2. An attachment for hammers and hatchets,
consisting of a body portion having a threaded 95
shank, a pointed prong, and a knife, all in-
integral with the body, the prong and knife being
on opposite sides of the said body, and an
internally-threaded socket having barbed
flanges thereon, substantially as herein shown 100
and described.

3. A hammer or hatchet provided with an
internally-screw-threaded socket secured in
the end of the handle, which projects into

the eye of the hammer or hatchet, whereby the socket is made to serve as a means for attaching a tool thereto and for securing the handle therein, substantially as described.

5 4. The combination, with a hammer or hatchet, of a socket adapted to enter the handle of the hammer or hatchet within the hammer or hatchet head, said socket having barbed flanges thereon and an internal screw-

thread therein, and a tool having a threaded 10 shank to fit the socket and having on one side a pointed prong and on another side a knife, substantially as described.

CHARLES E. HARRIS.
